**TABULATING MECHANISM FOR TYPEWRITER
OR LIKE MACHINES**

Leo Peter Frechette, Jr., Newington, Conn., assignor to
Royal McBee Corporation, New York, N. Y., a corpora-
tion of New York

Application August 6, 1956, Serial No. 602,320

19 Claims. (Cl. 197—178)

This invention relates to tabulating mechanism for typewriting or like machines, and more particularly to tabulating mechanism of the kind including a tabular stop on the main or stationary frame, a tabular stop on the traveling carriage, and mechanism for projecting one of the stops from a retracted position in which it is not engageable with the other of the stops to a projected position in which it is engageable with the other of the stops, and for returning the projected stop to its retracted position in response to engagement of the stops with each other and arresting of the carriage at the end of a tabulating run.

Mechanism embodying the invention is adapted for use generally in connection with typewriters or like machines of various kinds, but has special utility when incorporated in tabulating mechanisms of the "ten key decimal" or denominational kind in the operation of which depression of a selected one of a plurality of tabulator keys will effect movement of the carriage to a predetermined columnar or decimal position. A number of such mechanisms, previously known, have included a carrier or auxiliary carriage mounted on the main frame and supporting a plurality of stop devices or fingers normally in retracted positions in which they are out of the path of a cooperable stop on the main traveling carriage. The auxiliary carriage or stop carrier is spring urged toward the operator's right, that is in the direction of return travel of the main carriage, against a limit stop. In the performance of a tabulating operation, the main carriage is released from the control of the usual escapement mechanism so as to run to the left, and a selected one of the carrier supported stops is moved into projected position in which it is in the path of the carriage mounted stop, the escapement releasing and stop projecting parts being latched in their actuated positions. As the main carriage approaches the end of its tabulating run, the carriage mounted stop engages the projected carrier supported stop and moves the latter together with the other carrier supported stops and the carrier itself to the left against the spring urge or bias constantly exerted on the carrier until the carrier has moved against a limit stop, thus arresting the carriage in its predetermined tabulated position. The leftward movement of the carrier unlatches the escapement disabling and stop projecting parts, enabling them to be restored to their normal positions.

The previously known mechanisms referred to have generally been effective and reliable in operation when a carriage has performed a fairly long tabulating run and has acquired sufficient speed and kinetic energy to overcome the spring bias constantly exerted on the stop carrier, but have not always operated satisfactorily when the carriage has performed relatively short runs and has not acquired sufficient kinetic energy to insure movement of the stop carrier to its latch disabling position.

2

An object of the present invention is to provide tabulating mechanism of the kind referred to embodying constructional improvements by which the difficulties of the previously known mechanisms referred to are overcome, and reliable and certain operation is insured when the traveling carriage is performing either long or short tabulating runs.

Another object of the invention is to provide an improved tabulating mechanism of the character stated in which initiation of a tabulating operation renders the stop carrier free to be moved to its latch releasing position without being biased or restrained when the carriage mounted stop engages the carrier mounted stop.

A further object of the invention is to provide such a mechanism in which the stop carrier is normally biased in the direction of carriage return travel, and which includes debiasing means for disabling the biasing means and rendering the carrier free to be shifted in the carriage character spacing travel direction.

Other objects of the invention will become apparent from a reading of the following description of a preferred constructional form, the appended claims, and the accompanying drawings, in which:

Figure 1 is a fragmentary perspective view of mechanism embodying the invention, some parts being shown in vertical section;

Figure 2 is a reduced scale fragmentary top plan view of the mechanism shown in Figure 1, stationary frame parts being shown in horizontal section;

Figure 3 is a fragmentary top plan view, drawn on an enlarged scale, of tabular stop latch and biasing mechanism, the latch parts being shown in full lines in their normal positions and in dotted lines in intermediate operating positions;

Figure 4 is a fragmentary top plan view similar to Figure 3 but showing biasing mechanism in full lines in its normal position and in dotted lines in its operated position; and

Figure 5 is a fragmentary view, partly in vertical section, front to rear, of the machine and partly in elevation, drawn on a reduced scale.

The typewriting mechanism shown by way of example as embodying the invention in a preferred form is generally similar in many respects to the Royal standard office typewriter and the Royal electric typewriter. It includes a main frame element, parts of which are shown at A, provided with a lower track or rail 1 on which a carriage element B, including end plates 2 and 3, is mounted for letter spacing and return movements by means of a carriage or top rail 4 and ball rollers, one of which is shown at 5 in Figure 5. The carriage B is equipped with the usual cylinder or platen C.

Type bars, not shown, are suitably mounted on the frame, for example on a frame-supported case-shifting segment, the type bars and segment being operable by mechanism of any suitable kind, preferably power driven mechanism. Rearwardly extending end plate parts, one of which is shown at 3a in Figure 5, serve to mount a support, generally designated 6, for a plurality of tabular means or stops 7—7'.

The carriage B is urged to the left in the direction of the arrow a in Figure 1, that is, in the character spacing direction, by suitable mechanism, for example including a conventional spring drum, not shown, and a draw band connected by a clip 11 to an ear 11a on the right-hand carriage end plate 2 as shown in Figure 5. Feeding of the carriage to the left under the urge of the driving mechanism is controlled by escapement mecha-

nism illustrated partially as including a rack 12 carried by an angle bar 13 having rearwardly extending arms, one of which is shown at 14, pivotally mounted on the carriage at 15. Springs, one of which is shown at 16, connected to the arms 14 and anchored to the carriage, normally condition the feed controlling mechanism for effecting character spacing carriage travel by holding the escapement rack 12 in the position shown in full lines in Figure 5, in which the rack meshes with an escapement pinion 18 journalled on a shaft carried by a frame-mounted bracket 19. The pinion 18 is fast with an escapement wheel 20 adapted to rotate on the pinion shaft and to cooperate with escapement pawls or dogs, not shown, which may be of the kind and operated in the manner disclosed, for example, in Patent No. 2,563,722, granted August 7, 1951, to Henry J. Hart.

In operation, when the escapement dog mechanism is actuated, the wheel 20 is permitted to turn in step-by-step increments so as to permit the rack 12 and, consequently, the carriage to be fed to the left in incremental letter or character spacing movements.

The tabulating mechanism includes the support 6, comprising upper and lower rack bars 21 and 22 respectively formed with transverse grooves which register with each other and which are spaced longitudinally of the rack bars at character space intervals. Mounted on the stop frame 6 are a plurality of the laterally settable stop devices, several of which are designated 7 and are shown in their normal or inoperative positions, and another of which is designated 7' and is shown in its rearwardly projected or operative position. The tabular stops 7—7' are similar to individual stops disclosed in the patent to Myers et al. No. 1,892,071, dated December 27, 1932. Each tabular stop can be shifted transversely of the frame 6 to an operative position at 7' or to an inoperative position shown at 7, and be frictionally and yieldably maintained in whichever position it has been set by a spring 7a.

When a tabular stop is set in its operative position as shown at 7', its rear edge projects toward the back of the machine sufficiently to be engaged by one of a plurality of frame mounted tabular stop devices adapted selectively to be moved into or out of the path of the operatively positioned stop 7'. In the illustrative embodiment of the invention, the frame mounted stop devices are of such construction that when one has been moved to operative position it will be set or latched automatically to remain there until a tabulating operation has been completed without its being necessary for a key or other mechanism, which caused movement of the device to operative position, to be held depressed or otherwise in operated position.

Many of the parts described above are of known construction and relative arrangement. The invention relates more particularly to other parts to be described hereinafter, and to the combination of such other parts with parts already described.

The illustrative embodiment includes ten tabular stop devices formed as blades or fingers 23 mounted on a carrier generally designated 24 and comprising a shaft or rod 25 extending through and being slidable in spaced frame brackets or walls A¹ and A². Secured to the shaft or rod 25 is a U-shaped frame or strap 26 the forwardly extending sides 26^a and 26^b of which are disposed close to the frame walls A¹ and A² respectively with sufficient clearance to permit the shaft 25 and frame 26 to shift relatively to the main frame A in the direction of carriage travel. The stop devices 23 are mounted close to one another on the shaft 25 so as to shift conjointly with the shaft and with each other when the carrier 24 is shifted parallel to the carriage travel. The stop devices 23 are individually rockable about the axis of the shaft 25 transversely to the carriage travel, and are normally held in retracted positions by individual normalizing springs 27 connected between an anchor plate 28 fixed to the frame 26 and rearwardly extending ears

29 on the upper ends of the respective stop devices 23. When the stop devices 23 are in their normal positions under the urge of the springs 27 their forward upper portions are retracted so as not to be engageable by the operatively positioned tabular stop 7' on the carriage during character spacing movement of the latter. The stop devices 23 are, however, adapted to be rocked counterclockwise into projected positions in which their forward upper portions are disposed in the path of and are thus engageable by the operatively positioned tabular stop means 7' as the latter moves in the character spacing direction with the carriage. The stop devices 23 are movable selectively and individually into such projected positions by key controlled mechanism to be described, one of the stop devices being shown in its operated or projected position at 23' in Figure 2 and in dotted lines in Figure 5.

The key controlled setting means for effecting movement of the stops 23 to projected positions is so constructed that initial or partial depression of a key directly moves the stop 23 associated with that particular key partially to its projected position, the subsequent or continued depression of the key then effecting operation of power driven means for moving the selected stop 23 completely to its projected position for cooperation with the operatively positioned carriage mounted stop 7'. Figures 1 and 2 show a plurality of tabular keys 30, ten such keys being shown in Figure 2 for selectively effecting operation of the ten frame mounted stop devices 23. The connections between the several keys 30 and the respectively associated stop devices 23 and power mechanism are similar and only the connections associated with the rightmost key 30 are illustrated. As shown in Figure 1, the rightmost key 30 is pivoted at its lower end to a lever member 32 which is rockable on a frame mounted shaft 33. A link 34 is pivoted at its front end to a depending arm 35 on the lever 32, and is pivoted at its rear end to the lower arm 36^a of a lever generally designated 36 which is pivoted on the main frame by a shaft or rod 37. The upper arm 36^b of the lever 36 is pivotally connected to the front end of a link 38, the rear end of which is formed with a slot 39 which receives a headed stud 40 secured to the lower end of the rightmost tabular stop device 23.

In operation, when the rightmost key 30 is depressed the lever 32 is rocked clockwise so as to pull the link 34 forwardly and rock the lever 36 clockwise, thereby moving the link 38 rearwardly to cause the root of the slot 39 to press against the stud 40 and rock the rightmost stop device 23 counterclockwise against the urge of its normalizing spring 27. The rocking of the stop device 23 effected by initial depression of the key 30 with the cooperation of the link 34, lever 36 and link 38 moves the stop device 23 only partially toward its projected position and requires little manual effort since the normalizing spring 27 is weak and is only partially stretched during this phase of the operation.

The partial rocking of the stop device 23 during the initial depression of the key also conditions the stop device for being rocked by power operated means completely to its projected position. The power operated means includes a frame mounted shaft 41 to which is secured an actuator bail 42 formed with a stop setting cam edge 42^a cooperable with the lower edge 43 of a nose depending from the stop device 23. In operation, when the stop device 23 has been rocked partially toward its projected position by initial depression of the key 30, the nose edge 43 will be disposed above the bail cam edge 42^a so that when the shaft 41 and bail 42 are rocked counterclockwise the cam edge 42^a will engage the nose edge 43 and force it rearwardly. This will complete rocking of the stop device 23 to its projected position wherein it is disposed for engagement with the operatively positioned stop 7' on the carriage for arresting the carriage at the end of a tabulating run.

Power driven means for rocking the shaft 41 and bail 42 includes a lever 44 mounted to rock about a frame mounted rod or shaft 45 and a link 46 connected at its front end to the lever 44 and at its rear end to a cushion lever generally designated 47 mounted on the shaft 41. The cushion lever 47 is of known construction, and includes a part 47^a fixed to the shaft 41 and a part 47^b pivoted at 47^c to the lever part 47^a. The lever part 47^b is formed with a slot 47^d which receives a headed stud 47^e on the lever part 47^a, the slot 47^d and stud 47^e cooperating with each other to limit rocking of the lever part 47^b with respect to the lever part 47^a about the pivot 47^c. A spring 47^f interposed between the down turned front end of the lever part 47^a and the down turned rear end of the lever part 47^b urges the lever parts 47^a and 47^b to the normal relative positions shown in Figure 1. In operation, when the lever 44 is rocked counterclockwise, the link 46 is pulled forwardly so as to tend to rock the lever part 47^b about its pivot 47^c on the lever part 47^a. Such rocking of the lever part 47^b on the lever part 47^a is yieldably resisted by the spring 47^f which transmits rocking effort to the lever part 47^a and causes the latter and the shaft 41 to rock counterclockwise under power drive, cushioned by the spring 47^f. A spring 48 connected at its upper end to the lever 44 and having its lower end anchored to the main frame A normally maintains the lever 44 and the associated parts in their inactive positions in which a stop ear 49 on a lever 50 secured to the shaft 41 abuts the frame part A as shown in Figure 1.

In order to condition the machine for the performance of a tabulating operation it is necessary not only to move a selected stop device 23 to its projected position, but also to condition the feed controlling escapement mechanism to render the carriage free to be driven uninterruptedly in the character spacing direction until arrested by engagement of the carriage mounted stop 7' with the projected stop device 23'. For so conditioning the feed controlling escapement mechanism, the lever 50 on the shaft 41 is formed at its free end with a rounded nose 50^a disposed immediately behind the depending part 51^a of a rack releasing lever 51 pivoted at 52 on the carriage B. The releasing lever 51 has a forwardly extending part 51^b projecting under the horizontal part of the angle bar 13 so that when the shaft 41 and lever 50 are rocked counterclockwise the lever 51 will be rocked clockwise, and the lever part 51^b will lift the angle bar 13 against the urge of the springs 16 to disengage the escapement rack 12 from the escapement pinion 18. In this way the feed controlling escapement mechanism is conditioned to permit a tabulating run of the carriage under the urge of the carriage driving mechanism.

In order that the carriage may complete its tabulating run without its being necessary for the key 30 to be held depressed, a retaining means or latch generally designated 53 is pivoted on the frame A at 54 and is adapted to cooperate with a latch arm 55 integral with the lever part 47^a secured to the shaft 41. When the parts are in their normal positions the latch arm 55 is disposed just behind an inclined cam surface 53^a on the latch 53, the cam surface 53^a terminating at its forward end at a latch retaining surface or nose 53^b. For constantly urging the latch 53 to rock clockwise and thus to bear against the latch arm 55, a lever 56 is pivoted at 57 on an extension 58^a of an arm 58 secured to the shaft or rod 25 by a set screw 58^d. A spring 59 having its opposite ends connected respectively to the rear end of the lever 56 and the arm extension 58^a constantly urges the lever 56 to rock counterclockwise so as to cause the front end of the lever 56 to press against a stud 60 on the rear end of the latch 53 and hold the stud against a latch resetting part 58^b on the arm 58.

When the parts are in their normal or inactive positions the carrier 24 is maintained at the rightmost limit of its shifting parallel to the direction of carriage travel by biasing means comprising a spring 61 interposed be-

tween a fixed bracket 62 and an ear 63^a on a biasing lever 63 pivoted at 64 on the frame A. The biasing lever 63 has a contact part 63^b which normally is pressed against a contact part 58^c on the arm 58 secured to the shaft 25, the arrangement being such that the spring 61 normally biases the lever 63 to rock clockwise and thus hold the arm 58 and carrier 24 toward the right.

In the operation of the mechanism thus for described, the parts normally will be positioned as shown in Figures 10 1 and 2 and in full lines in Figures 3, 4 and 5, the carrier 24 being in its rightmost or normal position with respect to the frame parts A¹ and A² and contacting the frame part A² with a small clearance existing between the left side of the carrier and the frame part A¹. When a key 15 30 is depressed initially the lever 32, link 34, lever 36 and link 38 are operated to move the associated stop device 23 partially toward its projected position in the manner previously described so as to position the stop device nose edge 43 immediately above the bail cam edge 42^a. Continued depression of the selected key 30 will cause the power driven means to be described later to rock the lever 44 counterclockwise against the urge of the spring 48 so as to move the link 46 forwardly, rock the shaft 41 and bail 42 counterclockwise, and complete the movement of the selected stop device to its projected position, at the same time operating the levers 50 and 51 to disengage the escapement rack 12 from the pinion 18 and condition the feed controlling mechanism to effect a tabulating run. The counterclockwise rocking 20 of the shaft 41 will cause the latch arm 55 to act upon the cam surface 53^a of the latch to deflect the latter counterclockwise until the latch arm 55 has moved beyond the retaining surface or nose 53^b whereupon the spring 59 and lever 56 will rock the latch 53 clockwise to place 25 the nose 53^b behind the latching arm 55. The latch 53 will then retain the shaft 41 in its operated position so as to maintain the selected stop device 23 in its projected position and maintain the feed controlling mechanism conditioned for tabulation.

As the carriage approaches the end of its tabulating run, the operatively positioned carriage mounted stop 7' engages the projected stop device 23' so as to move the latter, the companion stops 23 and the carrier 24 from their normal positions parallel to the carriage travel until 30 the left side 26^a of the carrier engages the frame part A¹, whereupon the carrier 24 and the carriage B are arrested with the stop 23' in its actuated position. The leftward shifting of the carrier 24 and the arm 58 on the carrier shaft 25 causes the latch resetting part or extension 58^b on the arm 58 to press against the resetting stud part 60 and rock the latch 53 counterclockwise, thus releasing the latch arm 55 and permitting the spring 48 to act through the lever 44, the link 46 and the lever 47 to rock the bail 42 clockwise and thus disengage the bail 42 from the stop nose 43. In this way the stop device 23' is rendered free to be returned to its retracted position by its normalizing spring 27. In the event the normalizing spring 27, which desirably is rather weak in order to minimize the manual effort required for conditioning the stop 35 23 for power operation, does not return the projected stop rapidly enough or completely to its retracted position, the bottom edge of the bail 42 will engage a cam surface 43^a at the lower end of the stop device 23 for positively rocking the stop device completely to its retracted position.

Mechanisms in which a stop device carrier, such as the carrier 24, are moved toward the left upon engagement of a carriage mounted stop with an operatively positioned frame mounted stop for effecting unlatching of the stop 40 70 positioning means have previously been known. In certain of the prior mechanisms of this class it has been necessary for leftward movement of the frame mounted stop carrier to be performed while the carrier is still biased toward the right or in the carriage return travel direction. While such known mechanisms have generally been

dependable in operation when the carriages have been performing relatively long tabulating runs and have, therefore, acquired kinetic energy to overcome the carrier bias, the prior mechanisms have frequently been uncertain in operation when the carriages have been called upon to perform relatively short tabulating runs, acquiring insufficient kinetic energy to overcome the carrier bias and to move the carriers to their leftmost limits as is required for unlatching the operating mechanisms. In accordance with the present invention, this difficulty is overcome and the unlatching of the operating mechanism is made certain for both relatively short tabulating runs and relatively long tabulating runs by the provision of debiasing means operable for disabling the carrier biasing mechanism automatically as a part of and preferably at the beginning of a tabulating operation. In the preferred construction shown, the biasing lever 63 is formed with a debiasing part or rounded nose 63^c which extends above the front end of the latch 53 and projects in front of the latch nose 53^b without engaging the latch arm 55 when the latter is in its normal position, retracted to the rear of the latch nose 53^b. Since the debiasing nose 63^c is thus normally free from restraint by the latch arm 55, the biasing spring 61 is normally enabled to urge the biasing lever 63 clockwise to cause its contact part 63^b to press against the contact part 58^c of the carrier shaft arm 58 and bias the carrier 24 toward the right.

When the shaft 41 is rocked counterclockwise for conditioning the feed controlling mechanism for enabling a tabulating run and for moving the selected stop 23 to projected position, the latch arm 55 moves forwardly and engages the debiasing nose 63^c so as to rock the biasing lever 63 counterclockwise to its operated position and disengage its contact part 63^b from the carrier arm contact part 58^c, the latch arm 55 and biasing lever 63 then being in the positions shown in dotted lines in Figure 4. With the parts so positioned, the carrier 24 is no longer subjected to the bias of the spring 61 so that when the carriage mounted stop 7' engages the projected frame mounted stop 23', the carrier 24 and all of the stops 23 may easily be shifted to the left without being restrained by the spring 61, the leftward shifting of the carrier 24 causing the latch 53 to be released as previously explained. The freedom of the carrier 24 and associated parts to be shifted to the left without restrained by the then disabled biasing spring 61 insures that the carrier will be shifted completely and the operating mechanism will be unlatched even when the carriage has moved through only a very short tabulating run and is moving slowly at the time of engagement of the stop 7' with the projected stop 23'.

Upon unlatching of the latch arm 55 and return clockwise rocking of the shaft 41 and bail 42 to their normal positions, the latch arm 55 will move rearwardly away from the debiasing nose 63^c so as to enable the spring 61 to rock the biasing lever 63 clockwise, causing the contact part 63^b to press against the contact part 58^c and shift the carrier 24 back to its normal position in contact with the frame part A². The parts will then all have been restored to their normal or starting positions so that the machine will be conditioned for continued typing operation, or for another tabulating operation.

Power driven mechanism generally designated D is provided for operating the link 46, shaft 41 and associated parts. Preferably, the power driven mechanism D is of the kind including a continuously running prime mover, such as a snatch roll 65, cooperable momentarily under key control with an actuator or pawl carrier 66 pivoted at 67 to the lever 44 for imparting a driving impulse of short duration to rock the lever 44 counterclockwise until the latch arm 55 has moved into latched engagement with the latch nose 53^b. The power driven mechanism shown is of the kind illustrated and described in detail in the patent to Kupper No. 2,567,945, dated September 18, 1951. The actuator 66 normally is urged upwardly or clockwise about the pivot 67 by a spring 68

connected at its lower end to the front end of the actuator 66 and anchored at its upper end to a fixed frame part, not shown. A pawl 69 pivoted on the actuator at 70 is urged to rock clockwise by a spring 71 connected to the pawl and the actuator, but normally is retained in the position shown in Figure 1, in which the pawl nose 69^a is above and out of contact with the toothed snatch roll 65, by a trigger, not shown. When the carrier 66 is rocked counterclockwise the trigger engages a frame mounted abutment, not shown, and is moved so as to release the pawl 69 and permit the spring 71 to rock the pawl clockwise and bring its nose 69^a into engagement with the snatch roll. The pawl 69 and the carrier 66 are then thrust forwardly so as to rock the lever 44 and pull the link 46 forwardly to operate the shaft 41 and associated parts. When the latch arm 55 has become latched by the latch 53 the pawl 69 will have been cast off from engagement with the snatch roll 65, but the pawl and the carrier 66 will be held in their operative positions by the latch 53. When the latch 53 is disengaged from the latch arm 55 by leftward movement of the stop carrier 24 and its extension arm 58, the spring 48 will rock the lever 44 clockwise to return the pawl carrier 66 to its normal position while the carrier 66 is held up by the spring 68 so that the pawl 69 will not re-engage the snatch roll 65 during return movement of the carrier 66. For a more detailed illustration and description of the power driven mechanism D, reference is made to the Kupper Patent No. 2,567,945.

For moving the carrier 66 downwardly to effect engagement of the pawl 69 with the snatch roll, the key operated lever 32 is formed with a rearwardly projecting finger 72 which overlies a bar 73 carried by arms 74 supported on the shaft 33, the arrangement being such that when any one of the keys 30 is depressed beyond the position in which it has moved its associated tabular stop device 23 to its intermediate position, the associated lever finger 72 will rock the rod and arm assembly 73, 74 clockwise so as to move a link 75 downwardly and rock a lever 76 clockwise about a pivot rod 77 supported on the main frame A. A spring 78 connected to the lever 76 and to the main frame A normally maintains the lever 76 in the position shown in Figure 1. When the lever 76 is rocked clockwise by depression of a key 30, a flipper 79 pivoted at 80 on the rear end of the lever 76 and urged clockwise by a spring 79^a presses against an ear 81 on the pawl carrier 66 for rocking the latter counterclockwise and bringing the pawl nose 69^a into engagement with the snatch roll 65, as previously explained. If the key 30 is held depressed until after the latch arm 55 has been released and the carrier 66 has consequently been permitted to return to its normal position, the carrier ear 81 will engage the flipper 79 during return movement of the carrier, but this movement will not be interrupted by the flipper because the latter will rock idly counterclockwise about its pivot 80 until the ear 81 has passed to the rear of the flipper.

Operation

Although phases of the operation of the mechanism have been explained in connection with the disclosure of several combinations and sub-combinations, a summary of a typical operating cycle may assist in understanding the invention.

Prior to the initiation of a tabulating operation the parts will be in the positions shown in Figure 1 and in full lines in Figures 3, 4 and 5, and the snatch roll 65 will be running continuously counterclockwise. The carrier 24 and all of the associated stop devices 23 will be biased toward the right and held in their normal positions by the spring 61 and biasing lever 63, all of the stop devices 23 being in their retracted positions. To initiate a tabulating run of the carriage B a key 30, for example the rightmost key shown in Figures 1 and 2, is depressed so as to rock the associated lever 32 and operate the link 34, lever 36 and link 38 to move the

selected stop device 23 to its intermediate position in which its depending nose edge 43 is disposed above the bail cam edge 42^a. Continued depression of the key 30 will cause the lever finger 72 to rock the rod and arm assembly 73, 74 and thereby move the pawl carrier 66 counterclockwise to effect engagement of the pawl nose 69^a with the snatch roll 65. The snatch roll will then drive the pawl 69 and carrier 66 forwardly to operate the lever 44, link 46 and shaft and bail assembly 41, 42 to move the stop setting bail edge 42^a into engagement with the nose edge 43 of the selected stop device 23 and cam the stop device into its fully projected position as shown at 23' in Figures 2 and 5 in which its upper and forward portion will be disposed in the path of the frame mounted stop 7'. Concomitantly with movement of the stop 23 to its projected position, the arm 50 on the shaft 41 will operate the rack releasing lever 51 to disengage the rack 12 from the escapement pinion 18 and enable the carriage to perform a tabulating run. The rocking of the shaft 41 for moving the stop device 23 to its projected position and disengaging the escapement rack 12 from the pinion 18 moves the latch arm 55 into engagement with the latch nose 53^b, and also into engagement with the debiasing nose 63^c of the biasing lever 63 so as to rock the latter into the position shown in dotted lines in Figure 4. This disengages the contact part 58^c on the lever 63 from the contact part 58^b on the carrier arm 58, thereby removing the bias from the carrier and conditioning it to be moved freely toward the left. When the carriage approaches the end of its tabulating run, the stop 7' engages the projected stop device 23' and moves the latter together with the retracted stop devices 23 and the carrier 24 toward the left until arrested by engagement of the carrier frame side 26^a with the fixed frame part A¹. Since this leftward movement of the carrier 24 and stop devices 23 and 23' takes place without restraint by the biasing spring 61, movement of the carrier and supported stop devices 23, 23' completely to their leftmost positions is insured even though the carriage has performed only a short tabulating run and has acquired only a small amount of kinetic energy.

Leftward movement of the carrier 24 causes the resetting part 58^b on the carrier arm 58 to press against the resetting part 60 on the latch 53 to rock the latch counter-clockwise and release the latch arm 55, thereby permitting the arm 55 and associated parts to be returned to their normal positions by the spring 48. Clockwise rocking of the bail 42 under the urge of the spring 48 will release the projected stop for being returned to its normal position by the associated spring 27, and if the projected stop is not fully returned by the relatively weak spring 27 the lower edge of the bail 42 will engage the stop cam surface 43^a to rock the stop 23' to its retracted position under the urge of the relatively stronger spring 48.

Restoration of the latch arm 55 to its normal position by the spring 48 will also reactivate the biasing lever 63 and spring 61 to cause the contact part 63^b to press against the contact part 58^c on the carrier arm 58 and move the carrier 24 and stops 23 toward the right until arrested by engagement of the carrier frame side 26^b with the fixed frame part A². Rocking of the shaft 41 by the spring 48 upon unlatching of the arm 55 will deactivate the escapement releasing lever 51. The machine will then be conditioned for typing or for the performance of another tabulating operation.

The mechanism disclosed embodies the invention in a preferred form, but it is intended that the disclosure be illustrative rather than definitive, the invention being defined in the claims.

I claim:

1. In a typewriter or like machine, the combination of a frame element; a carriage element mounted on said frame element for character spacing and return travel; mechanism for driving said carriage element in the char-

acter spacing direction; feed controlling mechanism normally conditioned for effecting character spacing movements of said carriage element and being conditionable for enabling tabulating runs of said carriage element; tabular stop means on one of said elements; a tabular stop device; means mounting said tabular stop device on the other of said elements for movement transversely of the direction of carriage element travel from a retracted position in which it is not engageable with said tabular stop means into a projected position in which said tabular stop device is engageable with said tabular stop means for arresting said carriage element at the end of a tabulating run, said mounting means also mounting said tabular stop device for movement parallel to the carriage element travel from a normal position to an actuated position; biasing means for urging said tabular stop device parallel to the carriage element travel toward its normal position and for normally maintaining said tabular stop device in its said normal position; means for conditioning said feed controlling mechanism for enabling a tabulating run of said carriage element; setting means for moving said tabular stop device from its retracted position to its projected position; and debiasing means for disabling said biasing means to permit said tabular stop device to be moved to its actuated position by said tabular stop means when engaged thereby without being restrained by said biasing means.

2. In a typewriter or like machine, the combination of a frame element; a carriage element mounted on said frame element for character spacing and return travel; mechanism for driving said carriage element in the character spacing direction; feed controlling mechanism normally conditioned for effecting character spacing movements of said carriage element and being conditionable for enabling tabulating runs of said carriage element; tabular stop means on one of said elements; a tabular stop device; means mounting said tabular stop device on the other of said elements for movement transversely of the direction of carriage element travel from a retracted position in which it is not engageable with said tabular stop means into a projected position in which said tabular stop device is engageable with said tabular stop means for arresting said carriage element at the end of a tabulating run, said mounting means also mounting said tabular stop device for movement parallel to the carriage element travel from a normal position to an actuated position; biasing means for urging said tabular stop device parallel to the carriage element travel toward its normal position and for normally maintaining said tabular stop device in its said normal position; means for conditioning said feed controlling mechanism for enabling a tabulating run of said carriage element; setting means for moving said tabular stop device from its retracted position to its projected position; and debiasing means for disabling said biasing means to permit said tabular stop device to be moved to its actuated position by said tabular stop means when engaged thereby without being restrained by said biasing means; and manually controlled means for operating said setting means, said conditioning means and said debiasing means.

3. In a typewriter or like machine, the combination of a frame element; a carriage element mounted on said frame element for character spacing and return travel; mechanism for driving said carriage element in the character spacing direction; feed controlling mechanism normally conditioned for effecting character spacing movements of said carriage element and being conditionable for enabling tabulating runs of said carriage element; tabular stop means on one of said elements; a tabular stop device; means mounting said tabular stop device on the other of said elements for movement transversely of the direction of carriage element travel from a retracted position in which it is not engageable with said tabular stop means into a projected position in which said tabular stop device is engageable with said tabular stop means for arresting said carriage element at the end of a tabu-

lating run, said mounting means also mounting said tabular stop device for movement parallel to the carriage element travel from a normal position to an actuated position; biasing means for urging said tabular stop device parallel to the carriage element travel toward its normal position and for normally maintaining said tabular stop device in its said normal position; means for conditioning said feed controlling mechanism for enabling a tabulating run of said carriage element; setting means for moving said tabular stop device from its retracted position to its projected position; debiasing means for disabling said biasing means to permit said tabular stop device to be moved to its actuated position by said tabular stop means when engaged thereby and while free of restraint by said biasing means.

4. In a typewriter or like machine, the combination of a frame element; a carriage element mounted on said frame element for character spacing and return travel; mechanism for driving said carriage element in the character spacing direction; feed controlling mechanism normally conditioned for effecting character spacing movements of said carriage element and being conditionable for enabling tabulating runs of said carriage element; tabular stop means on one of said elements; a tabular stop device; means mounting said tabular stop device on the other of said elements for movement transversely of the direction of carriage element travel from a retracted position in which it is not engageable with said tabular stop means into a projected position in which said tabular stop device is engageable with said tabular stop means for arresting said carriage element at the end of a tabulating run, said mounting means also mounting said tabular stop device for movement parallel to the carriage element travel from a normal position to an actuated position; biasing means for urging said tabular stop device parallel to the carriage element travel toward its normal position and for normally maintaining said tabular stop device in its said normal position; means for conditioning said feed controlling mechanism for enabling a tabulating run of said carriage element; setting means for moving said tabular stop device from its retracted position to its projected position; debiasing means for disabling said biasing means to permit said tabular stop device to be moved to its actuated position by said tabular stop means when engaged thereby without being restrained by said biasing means; power driven means; manually operable means; and means responsive to operation of said manually operable means for effecting operation of said setting means, said conditioning means and said debiasing means by said power driven means.

5. In a typewriter or like machine, the combination of a frame element; a carriage element mounted on said frame element for character spacing and return travel; mechanism for driving said carriage element in the character spacing direction; feed controlling mechanism normally conditioned for effecting character spacing movements of said carriage element and being conditionable for enabling tabulating runs of said carriage element; tabular stop means on one of said elements; a tabular stop device; means mounting said tabular stop device on the other of said elements for movement transversely of the direction of carriage element travel from a retracted position in which it is not engageable with said tabular stop means into a projected position in which said tabular stop device is engageable with said tabular stop means for arresting said carriage element at the end of a tabulating run, said mounting means also mounting said tabular stop device for movement parallel to the carriage element travel from a normal position to an actuated position; biasing means for moving said tabular stop device parallel to the carriage element travel from its actuated

position to its normal position and for normally maintaining said tabular stop device in its said normal position; means for conditioning said feed controlling mechanism for enabling a tabulating run of said carriage element; setting means for moving said tabular stop device from its retracted position to its projected position; and debiasing means for disabling said biasing means to permit said tabular stop device to be moved to its actuated position by said tabular stop means when engaged thereby and while free of restraint by said biasing means.

6. In a typewriter or like machine, the combination of a frame element; a carriage element mounted on said frame element for character spacing and return travel; mechanism for driving said carriage element in the character spacing direction; feed controlling mechanism normally conditioned for effecting character spacing movements of said carriage element and being conditionable for enabling tabulating runs of said carriage element; tabular stop means on one of said elements; a tabular stop device; means mounting said tabular stop device on the other of said elements for movement transversely of the direction of carriage element travel from a retracted position in which it is not engageable with said tabular stop means into a projected position in which said tabular stop device is engageable with said tabular stop means for arresting said carriage element at the end of a tabulating run, said mounting means also mounting said tabular stop device for movement parallel to the carriage element travel from a normal position to an actuated position; biasing means for moving said tabular stop device parallel to the carriage element travel from its actuated position to its normal position and for normally maintaining said tabular stop device in its said normal position; means for conditioning said feed controlling mechanism for enabling a tabulating run of said carriage element; setting means for moving said tabular stop device from its retracted position to its projected position; debiasing means for disabling said biasing means to permit said tabular stop device to be moved to its actuated position by said tabular stop means when engaged thereby and while free of restraint by said biasing means; power driven means; a key; means responsive to operation of said key for effecting operation of said setting means and said conditioning means and for effecting operation of said debiasing means by said power driven means; and means responsive to movement of said tabular stop device to its actuated position for restoring said tabular stop device to its retracted position, deactivating said conditioning means to prepare said feed controlling mechanism for effecting character spacing movements of said carriage element, and deactivating said debiasing means whereby to enable said biasing means to restore said tabular stop device to its normal position.

7. In a typewriter or like machine, the combination of a frame element; a carriage element mounted on said frame element for character spacing and return travel; mechanism for driving said carriage element in the character spacing direction; feed controlling mechanism normally conditioned for effecting character spacing movements of said carriage element and being conditionable for enabling tabulating runs of said carriage element; tabular stop means on one of said elements; a tabular stop device; means mounting said tabular stop device on the other of said elements for movement transversely of the direction of carriage element travel from a retracted position in which it is not engageable with said tabular stop means into a projected position in which said tabular stop device is engageable with said tabular stop means for arresting said carriage element at the end of a tabulating run, said mounting means also mounting said tabular stop device for movement parallel to the carriage element travel from a normal position to an actuated position; biasing means for urging said tabular stop device parallel to the carriage element travel toward its normal position and for normally maintaining said tabular stop device in its said normal position; means for

conditioning said feed controlling mechanism for enabling a tabulating run of said carriage element; setting means for moving said tabular stop device from its retracted position to its projected position; debiasing means for disabling said biasing means to permit said tabular stop device to be moved to its actuated position by said tabular stop means when engaged thereby without being restrained by said biasing means; manually controlled means for effecting operation of said setting means, said conditioning means and said debiasing means; retaining means for releasably holding said tabular stop device in its projected position and for releasably holding said debiasing means and said conditioning means in operated positions; and means responsive to movement of said tabular stop device parallel to the carriage element travel from its normal position to its actuated position by said tabular stop means for releasing said retaining means to enable said tabular stop device to be returned to its retracted position, for deactivating said conditioning means, and for releasing said debiasing means to enable said biasing means to move said tabular stop device to its normal position at the conclusion of a tabulating run.

8. In a typewriter or like machine, the combination of a frame element; a carriage element mounted on said frame element for character spacing and return travel; mechanism for driving said carriage element in the character spacing direction; feed controlling mechanism normally conditioned for effecting character spacing movements of said carriage element and being conditionable for enabling tabulating runs of said carriage element; tabular stop means on one of said elements; a tabular stop device; means mounting said tabular stop device on the other of said elements for movement transversely of the direction of carriage element travel from a retracted position in which it is not engageable with said tabular stop means into a projected position in which said tabular stop device is engageable with said tabular stop means for arresting said carriage element at the end of a tabulating run, said mounting means also mounting said tabular stop device for movement parallel to the carriage element travel from a normal position to an actuated position; biasing means for urging said tabular stop device parallel to the carriage element travel toward its normal position and for normally maintaining said tabular stop device in its said normal position; means for conditioning said feed controlling mechanism for enabling a tabulating run of said carriage element; setting means for moving said tabular stop device from its retracted position to its projected position; debiasing means for disabling said biasing means to permit said tabular stop device to be moved to its actuated position by said tabular stop means when engaged thereby without being restrained by said biasing means; power driven means; a key; means responsive to operation of said key for effecting operation of said conditioning means, said setting means and said debiasing means by said power driven means; retaining means for releasably holding said tabular stop device in its projected position and releasably holding said conditioning means and said debiasing means in their operated positions; and means responsive to movement of said tabular stop device parallel to the carriage element travel from its normal position to its actuated position by said tabular stop means for releasing said retaining means to deactivate said conditioning means, to enable said tabular stop device to be returned to its retracted position and to release said debiasing means and enable said biasing means to move said tabular stop device to its normal position, all at the conclusion of a tabulating run of said carriage element.

9. In a typewriter or like machine, the combination of a frame element; a carriage element mounted on said frame element for character spacing and return travel; mechanism for driving said carriage element in the character spacing direction; feed controlling mechanism

normally conditioned for effecting character spacing movements of said carriage element and being conditionable for enabling tabulating runs of said carriage element; tabular stop means on one of said elements; a tabular stop device; means mounting said tabular stop device on the other of said elements for movement transversely of the direction of carriage element travel from a retracted position in which it is not engageable with said tabular stop means into a projected position in which said tabular stop device is engageable with said tabular stop means for arresting said carriage element at the end of a tabulating run, said mounting means also mounting said tabular stop device for movement parallel to the carriage element travel from a normal position to an actuated position, a first contact part connected to and being movable simultaneously with said tabular stop device when the latter is moved parallel to the carriage element travel; a second contact part engageable with said first contact part; biasing means for normally pressing said second contact part against said first contact part to move said tabular stop device to and maintain it in its normal position; setting means for moving said tabular stop device from its retracted position to its projected position; means for conditioning said feed controlling mechanism for enabling a tabulating run of said carriage element; and debiasing means for disengaging said second contact part from said first contact part thereby to permit said tabular stop device to be moved freely by said tabular stop means when engaged thereby as said carriage element approaches the end of a tabulating run.

10. In a typewriter or like machine, the combination of a frame element; a carriage element mounted on said frame element for character spacing and return travel; mechanism for driving said carriage element in the character spacing direction; feed controlling mechanism normally conditioned for effecting character spacing movements of said carriage element and being conditionable for enabling tabulating runs of said carriage element; tabular stop means on one of said elements; a tabular stop device; means mounting said tabular stop device on the other of said elements for movement transversely of the direction of carriage element travel from a retracted position in which it is not engageable with said tabular stop means into a projected position in which said tabular stop device is engageable with said tabular stop means for arresting said carriage element at the end of a tabulating run, said mounting means also mounting said tabular stop device for movement parallel to the carriage element travel from a normal position to an actuated position; a first contact part connected to and being movable simultaneously with said tabular stop device when the latter is moved parallel to the carriage element travel; a second contact part engageable with said first contact part; biasing means for normally pressing said second contact part against said first contact part to move said tabular stop device to and maintain it in its normal position; setting means for moving said tabular stop device from its retracted position to its projected position; means for conditioning said feed controlling mechanism for enabling a tabulating run of said carriage element; debiasing means for disengaging said second contact part from said first contact part thereby to permit said tabular stop device to be moved freely by said tabular stop means when engaged thereby as said carriage element approaches the end of a tabulating run; key controlled power driven means for operating said setting means, said conditioning means and said debiasing means; a latch for releasably maintaining said setting means, said conditioning means and said debiasing means in operated positions; and means responsive to movement of said tabular stop device from its normal position to its actuated position by said tabular stop means for releasing said latch thereby to effect restoration of said tabular stop device to its retracted position, deactivation of said conditioning means

and said debiasing means, and reactivation of said biasing means.

11. In a typewriter or like machine, the combination of a frame; a carriage mounted on said frame for character spacing and return travel; mechanism for driving said carriage in the character spacing direction; feed controlling mechanism normally conditioned for effecting character spacing movements of said carriage and being conditionable for enabling tabulating runs of said carriage; tabular stop means on said carriage; a shaft mounted on said frame for movement parallel to the direction of carriage travel; a tabular stop device mounted on said shaft for rocking about the shaft axis from a retracted position in which said tabular stop device is displaced from the path of travel of said tabular stop means into a projected position in which said tabular stop device is in said path, said tabular stop device being movable conjointly with said shaft parallel to the direction of carriage character spacing travel from a normal position to an actuated position; a first contact part fixed with respect to said shaft; a biasing lever having a second contact part engageable with said first contact part; a spring normally urging said lever to rock to a normal position in which said second contact part presses against said first contact part in the carriage return travel direction for maintaining said tabular stop device in its normal position; key controlled power operated means for conditioning said feed controlling mechanism to enable a tabulating run of said carriage, for moving said tabular stop device from its retracted position to its projected position and for rocking said biasing lever to an operated position against the urge of said spring to disengage said second contact part from said first contact part and render said shaft and said tabular stop device free to be moved in the character spacing direction; a latch for releasably maintaining said power operated means in operated position; a first resetting part fixed with respect to said shaft; a second resetting part on said latch and being operable by said first resetting part for releasing said latch when said shaft is moved in the character spacing direction by engagement of said tabular stop means with said tabular stop device as said carriage approaches the end of a tabulating run; and means responsive to releasing of said latch for restoring said tabular stop device to its retracted position, for enabling said spring to rock said biasing lever to its normal position and for reconditioning said feed controlling mechanism for effecting character spacing movements of said carriage.

12. In a typewriter or like machine, the combination of a frame element; a carriage element mounted on said frame element for character spacing and return travel; mechanism for driving said carriage element in the character spacing direction; feed controlling mechanism normally conditioned for effecting character spacing movements of said carriage element and being conditionable for enabling tabulating runs of said carriage element; tabular stop means on one of said elements; a carrier mounted on the other of said elements for movement parallel to the carriage element travel from a normal position to an actuated position; a plurality of tabular stop devices mounted on said carrier for conjoint movement therewith parallel to the carriage element travel and for individual movement transversely of the direction of carriage element travel from retracted positions in which said tabular stop devices are not engageable with said tabular stop means into projected positions in which said tabular stop devices are engageable with said tabular stop means and vice versa; biasing means for urging said carrier to and maintaining it in its normal position; means for conditioning said feed controlling mechanism for enabling a tabulating run of said carriage element; setting means for moving a selected one of said tabular stop devices from its retracted position to its projected position; and debiasing means for disabling said biasing means to

permit said carrier to be moved without being restrained by said biasing means when said tabular stop means and the selected tabular stop device are in mutual engagement as the carriage element approaches the end of a tabulating run.

13. In a typewriter or like machine, the combination of a frame element; a carriage element mounted on said frame element for character spacing and return travel; mechanism for driving said carriage element in the character spacing direction; feed controlling mechanism normally conditioned for effecting character spacing movements of said carriage element and being conditionable for enabling tabulating runs of said carriage element; tabular stop means on one of said elements; a carrier mounted on the other of said elements for movement parallel to the carriage element travel from a normal position to an actuated position; a plurality of tabular stop devices mounted on said carrier for conjoint movement therewith parallel to the carriage element travel and for individual movement transversely of the direction of carriage element travel from retracted positions in which said tabular stop devices are not engageable with said tabular stop means into projected positions in which said tabular stop devices are engageable with said tabular stop means and vice versa; biasing means for urging said carrier to and maintaining it in its normal position; means for conditioning said feed controlling mechanism for enabling a tabulating run of said carriage element; setting means for moving a selected one of said tabular stop devices from its retracted position to its projected position; debiasing means for disabling said biasing means to permit said carrier to be moved without being restrained by said biasing means when said tabular stop means and the selected tabular stop device are in mutual engagement as the carriage element approaches the end of a tabulating run; and manually controlled means for operating said conditioning means, said setting means and said debiasing means.
14. In a typewriter or like machine, the combination of a frame element; a carriage element mounted on said frame element for character spacing and return travel; mechanism for driving said carriage element in the character spacing direction; feed controlling mechanism normally conditioned for effecting character spacing movements of said carriage element and being conditionable for enabling tabulating runs of said carriage element; tabular stop means on one of said elements; a carrier mounted on the other of said elements for movement parallel to the carriage element travel from a normal position to an actuated position; a plurality of tabular stop devices mounted on said carrier for conjoint movement therewith parallel to the carriage element travel and for individual movement transversely of the direction of carriage element travel from retracted positions in which said tabular stop devices are not engageable with said tabular stop means into projected positions in which said tabular stop devices are engageable with said tabular stop means and vice versa; biasing means for urging said carrier to and maintaining it in its normal position; means for conditioning said feed controlling mechanism for enabling a tabulating run of said carriage element; setting means for moving a selected one of said tabular stop devices from its retracted position to its projected position; debiasing means for disabling said biasing means to permit said carrier to be moved without being restrained by said biasing means when said tabular stop means and the selected tabular stop device are in mutual engagement as the carriage element approaches the end of a tabulating run; power driven means; and manually operable means for effecting operation of said conditioning means and said setting means and for effecting operation of said debiasing means by said power driven means.
15. In a typewriter or like machine, the combination of a frame element; a carriage element mounted on said frame element for character spacing and return travel;

mechanism for driving said carriage element in the character spacing direction; feed controlling mechanism normally conditioned for effecting character spacing movements of said carriage element and being conditionable for enabling tabulating runs of said carriage element; tabular stop means on one of said elements; a carrier mounted on the other of said elements for movement parallel to the carriage element travel from a normal position to an actuated position; a plurality of tabular stop devices mounted on said carrier for conjoint movement therewith parallel to the carriage element travel and for individual movement transversely of the direction of carriage element travel from retracted positions in which said tabular stop devices are not engageable with said tabular stop means into projected positions in which said tabular stop devices are engageable with said tabular stop means and vice versa; biasing means for urging said carrier to and maintaining it in its normal position; means for conditioning said feed controlling mechanism for enabling a tabulating run of said carriage element; setting means for moving a selected one of said tabular stop devices from its retracted position to its projected position; debiasing means for disabling said biasing means to permit said carrier to be moved without being restrained by said biasing means when said tabular stop means and the selected tabular stop device are in mutual engagement as the carriage element approaches the end of a tabulating run; power driven means; manually operable means; and means responsive to operation of said manually operable means for effecting operation of said conditioning means, said setting means and said debiasing means by said power driven means.

16. In a typewriter or like machine, the combination of a frame element; a carriage element mounted on said frame element for character spacing and return travel; mechanism for driving said carriage element in the character spacing direction; feed controlling mechanism normally conditioned for effecting character spacing movements of said carriage element and being conditionable for enabling tabulating runs of said carriage element; tabular stop means on one of said elements; a carrier mounted on the other of said elements for movement parallel to the carriage element travel from a normal position to an actuated position; a plurality of tabular stop devices mounted on said carrier for conjoint movement therewith parallel to the carriage element travel and for individual movement transversely of the direction of carriage element travel from retracted positions in which said tabular stop devices are not engageable with said tabular stop means into projected positions in which said tabular stop devices are engageable with said tabular stop means and vice versa; biasing means for moving said carrier from its actuated position to and maintaining it in its normal position; means for conditioning said feed controlling mechanisms for enabling a tabulating run of said carriage element; setting means for moving a selected one of said tabular stop devices from its retracted position to its projected position; debiasing means for disabling said biasing means to permit said carrier to be moved without being restrained by said biasing means when said tabular stop means and the selected tabular stop device are in mutual engagement as the carriage element approaches the end of a tabulating run; power driven means; key means; means responsive to operation of said key means for effecting operation of said setting means and said conditioning means and for effecting operation of said debiasing means by said power driven means; and means responsive to movement of said carrier to its actuated position for restoring the selected tabular stop device to its retracted position, deactivating said conditioning means to prepare said feed controlling mechanism for effecting character spacing movements of said carriage element, and deactivating said debiasing means to enable said biasing means to restore said carrier to its normal position.

17. In a typewriter or like machine, the combination of a frame element; a carriage element mounted on said frame element for character spacing and return travel; mechanism for driving said carriage element in the character spacing direction; feed controlling mechanism normally conditioned for effecting character spacing movements of said carriage element and being conditionable for enabling tabulating runs of said carriage element; tabular stop means on one of said elements; a carrier mounted on the other of said elements for movement parallel to the carriage element travel from a normal position to an actuated position; a plurality of tabular stop devices mounted on said carrier for conjoint movement therewith parallel to the carriage element travel and for individual movement transversely of the direction of carriage element travel from retracted positions in which said tabular stop devices are not engageable with said tabular stop means into projected positions in which said tabular stop devices are engageable with said tabular stop means and vice versa; biasing means for moving said carrier from its actuated position to and maintaining it in its normal position; means for conditioning said feed controlling mechanism for enabling a tabulating run of said carriage element; setting means for moving a selected one of said tabular stop devices from its retracted position to its projected position; debiasing means for disabling said biasing means to permit said carrier to be moved without being restrained by said biasing means when said tabular stop means and the selected tabular stop device are in mutual engagement as the carriage element approaches the end of a tabulating run; power driven means; key means; means responsive to operation of said key means for effecting operation of said setting means and said conditioning means and for effecting operation of said debiasing means by said power driven means; latch means for releasably holding said responsive means in operated position; and means operable by movement of said carrier to its actuated position for releasing said latch means thereby to effect restoring of the selected tabular stop device to its retracted position, deactivating of said conditioning means to prepare said feed controlling mechanism for effecting character spacing movements of said carriage element and deactivating of said debiasing means to enable said biasing means to restore said carrier to its normal position.

18. In a tabulating mechanism, a carriage; a carrier; means mounting said carriage and said carrier for movements in parallel paths; a tabular stop means on said carriage; a tabular stop device mounted on said carrier for movement from a retracted position to a projected position for engagement with said tabular stop means; biasing means effective when said tabular stop device is in its retracted position for urging said carrier and the tabular stop device thereon parallel to said paths in a direction toward said tabular stop means; means for moving said tabular stop device from its retracted position to its projected position; means for retaining said tabular stop device in its projected position; means operable when said tabular stop device is moved from its retracted position to its projected position for disabling said biasing means to enable said carrier to be moved freely in the opposite direction upon engagement of said tabular stop means and said tabular stop device; and means responsive to movement of said carrier in said opposite direction for disabling said retaining means.

19. In a tabulating mechanism, a carriage, a carrier; means mounting said carriage and said carrier for movements in parallel paths; a tabular stop means on said carriage; a tabular stop device mounted on said carrier for movement from a retracted position to a projected position for engagement with said tabular stop means; spring means effective when said tabular stop device is in its retracted position for biasing said carrier and the tabular stop device thereon parallel to said paths in a direction toward said tabular stop means; means for moving said tabular stop device from its retracted position

to its projected position; means for retaining said tabular stop device in its projected position; debiasing means operable when said tabular stop device is moved from its retracted position to its projected position for disabling said spring means to enable said carrier to be moved freely in the opposite direction upon engagement of said tabular stop means and said tabular stop device; and means responsive to movement of said carrier in said opposite direction for disabling said retaining means.
